UNITED STATES PATENT OFFICE.

WILLIAM H. EVERE, OF LAKWOOD, OHIO, ASSIGNEE OF ONE-THIRD TO HERMAN SCHMITT AND ONE-THIRD TO WILIAM F. EIRICK, BOTH OF CLEVELAND, OHIO.

MOLD FOR SEGMENTAL STRUCTURES.

1,305,704.

Specification of Letters Patent. Patented June 3, 1919.

Application filed December 24, 1916. Serial No. 268,125.

To all whom it may concern:

Be it known that I, WILLIAM H. EVERE, a citizen of the United States, residing at Lakewood, in the county of Cuyahoga and State of Ohio, have invented certain new and useful Improvements in Molds for Segmental Structures, of which the following is a specification.

This invention relates to molds used for the production, in advance, of sections of concrete arches, sewers, and other conduits and the like, and has for its object to provide improved devices for the production of such blocks or segments.

It is the intention of the invention to provide means whereby these blocks or segments can be molded, and afterward used for the construction of arches, culverts or the like, the purpose being to mold the blocks at a central plant, from which they can be transported to the place where the structures are to be built, and by standardizing the sizes, such structures can be readily built in various forms and the production has advantages as compared to the erection of molds and construction of the culverts or the like *in situ*, as commonly practised and requiring special work at the place.

The segments or blocks produced by the means to be described may be provided with interlocking features and may also be reinforced by metal, if desired, and may be readily assembled by ordinary workmen.

The invention includes means whereby the segments or sections can be molded in multiple, the forms including a series of curved face plates which fit within each other, in connection with end plates or pieces which are set up therewith, the whole being clamped together after being properly positioned, and the cement can be poured in the several molds at the same time to form multiple segments of various sizes. The device also includes joined forms to produce bell joints or other interlocking joints at the ends and sides of the sections, so that when the blocks are assembled, a strong and rigid structure is produced.

With these and other objects in view, the invention is illustrated in the accompanying drawings in which Figure 1 is a top view of a multiple mold set up according to the invention. Figs. 2 and 3 are perspective views of different forms of plates. Fig. 4 is a perspective view of fillers or sections used

to produce interlocking joints. Fig. 5 is a perspective view of one of the positioners used to hold the forms in proper position. Fig. 6 is a plan view of one of the multiple end plates. Fig. 7 is a plan of a modification.

Referring specifically to the drawings, 6 indicate a series of curved metal face plates which may be rolled metal bent to proper shape. In Fig. 1 these are illustrated as 65 semicircular in section, but they may be of any curvature desired and bent on a single radius for round arches or on multiple radii for parabolic or other arches, and instead of being semi-circular they may describe a 70 smaller segment of a curve as in Fig. 2. Or, they may be tapered to describe the segment of the frustum of a cone, as indicated in Fig. 3.

In any event, they are set up one inside 75 the other, as indicated in Fig. 1, to produce a plurality of spaces therebetween in which segments of different sizes can be cast. They are preferably stood upright on edge, upon a suitable base.

The spaces between the plates are closed at the ends by means of end plates 7, one of which is shown in Fig. 6. These end plates are of sufficient width to extend across all the spaces at each end, and in order to make 85 interlocking joints at the side edges of the resulting blocks, the plates have offsets 8 extending along the same, these offsets being spaced apart according to the thickness of the blocks produced, whereby either grooves 90 or ribs are formed in said edges. The plates 7 are symmetrical and are reversed to produce a rib in one end of the blocks and a groove in the opposite end, as will appear from Fig. 1. The segmental and end plates 95 when set up are suitably clamped together and the material is poured into the spaces between the plates.

To produce interlocking recesses and projections in the ends of the cast segments or blocks, I provide segmental fillers which agree in cross section with the shape of the joint to be formed and these fillers 9 are set in position between the plates 6, at the ends thereof, the ends of the fillers being engaged 105 in notches 10 in opposite edges of the end plates 7, both at top and bottom thereof as the mold stands assembled. In order to confine the inner and outer plates 6 I provide segmental bars or positioners 11 the ends of 110

which are engaged in notches 12 at the end plates 7. The fillers 9 and the positioners 11 will, of course, have the same curvature as the plates 6, but will be of slightly greater length to project through the notches 10 and 12. These fillers and bars serve to hold the plates 6 in proper spaced relation, the fillers 9 also acting to produce recesses in the opposite ends of the cast blocks to form lap joints 13 or the like when the plugs are assembled in the work.

When the multiple mold is thus set up or assembled, the cement is poured, and after it is set, the end plates 7 are removed. This 15 releases the fillers and the segmental plates and the mold can then be taken down and the finished blocks removed. It is the intention to have a number of standard shapes and sizes of culverts or arches to be constructed and the blocks will be made in advance and supplied when and where necessary. Instead of producing curved blocks, they may be made straight, for use as risers to increase the capacity of a conduit or the 25 like by being interposed between the arch and the invert.

By the means described, multiple units can be cast at a great saving of time and labor and the molds can be quickly set up and 30 taken down. The curvature, length and other dimensions of the mold may be indefinitely multiplied by the use of different plates.

In the modified form shown in Fig. 7, the 35 plates 6 are placed apart and supported by metal reinforcements 20 consisting of wires or rods bent to form loops and cross-diagonals to correspond with the thickness of the block to be produced, and this rod is located 40 between the segmental plates and is embedded in the cement when the block is cast, serving prior thereto to position the plates.

What I claim is:—

1. A multiple mold comprising a plurality 45 of segmental plates standing in parallel relation, end plates fitting against the ends of said plates, and means engaging said end

and segmental plates to space the same apart and support the latter in position.

2. A multiple mold comprising a plurality 50 of face plates assembled side by side, end plates fitting against the ends thereof, and filler members engaging said end plates and extending along and between said face plates and adapted to support the same in position 55 and also form recesses in the cast.

3. A multiple mold comprising a plurality 60 of face plates standing side by side, end plates fitting against the ends thereof and provided with a plurality of offsets to produce ribs or grooves in the blocks cast, and fillers extending from one end plate to the other and located between the face plates to support the same and also form recesses in the said blocks.

4. A multiple mold comprising a plurality 65 of parallel face plates, end plates fitting against the ends thereof and having notched edges, and fillers engaging at their ends in said notches and extending between the face plates to support and space the same and also form recesses in the cast.

5. A mold comprising face plates, end plates at the ends thereof, and a rod extending 70 between the face plates and bent to contact at various points therewith to support and space the same.

6. A mold comprising face plates and end plates, and fillers located in supporting relation between the face plates and having interlocking engagement with the end plates.

7. A mold comprising a plurality of segmental face plates, end plates extending across the ends of the face plates, at opposite ends thereof, and curved supporting 85 members extending from one plate to the other and between the face plates, to hold the latter in position.

In testimony whereof, I do affix my signature in presence of two witnesses.

WILLIAM H. EVER.
